US00D442503S

(12) **United States Design Patent** (10) Patent No.: **US D442,503 S**
Lundbeck et al. (45) Date of Patent: ** May 22, 2001

(54) **HANDHELD BATTERY TESTER**

(75) Inventors: **Bryan R. Lundbeck**, Moroni; **Dale B. Henningson**, Manti, both of UT (US)

(73) Assignee: **Auto Meter Products, Inc.**, Sycamore, IL (US)

(**) Term: **14 Years**

(21) Appl. No.: **29/124,312**

(22) Filed: **Jun. 2, 2000**

(51) LOC (7) Cl. **10-04**

(52) U.S. Cl. **D10/77; D10/78**

(58) Field of Search .... D10/78, 77; 324/426; 320/132, 134, 136, DIG. 18, DIG. 21; 429/426, 429, 432, 433; 340/635, 636

(57) **CLAIM**

The ornamental design for handheld battery tester, as shown and described.

DESCRIPTION

FIG. 1 is a front perspective view;

FIG. 2 is an enlarged front perspective view;

FIG. 3 is a front elevational view;

FIG. 4 is a rear elevational view;

FIG. 5 is an end view, the opposite end being a mirror image thereof;

FIG. 6 is a top plan view; and,

FIG. 7 is a bottom plan view.

1 Claim, 6 Drawing Sheets

FIG. 2

FIG. 3**FIG. 4****FIG. 5**

FIG. 6**FIG. 7**
